DEMI-TASSE CUP

Lee d. Miller, 310 W. 72nd St., New York, N.Y.

Filed May 8, 1959, Ser. No. 55,836

Term of patent 14 years

(Cl. D44—9)

Figure 1 is a side elevational view of a demi-tasse cup embodying my new design;

Figure 2 is a top plan view thereof, and

Figure 3 is a vertical sectional view as seen on the line 3—3 of Figure 2.

The invention is characterized by an integral concave wall having a convex inner edge, said wall projecting inwardly from the upper edge of the cup to provide an upwardly facing shallow receptacle having an area substantially equal to one-half the area of the cup at its upper edge.

I claim:

The ornamental design for a demi-tasse cup, as shown and described.
